Fig. 5

FIGURE 1 is a perspective view of a restaurant building embodying my novel design, it being understood that the sides of the building are identical but reverse;

FIGURE 4 is a side elevational view, partly broken away and somewhat reduced from the showing in FIGURE 2, of the building shown in FIGURES 1 to 3; and

I claim:

The ornamental design for a restaurant building, as shown and described.
